KNITTING MACHINE

William J. Kuehnel, Sag Harbor, N. Y., assignor
of one-half to John G. G. Merrow, New York,
N. Y.

Application May 8, 1942, Serial No. 442,142

6 Claims. (Cl. 66—31)

This invention relates to knitting machines and more particularly to a knitting machine of the circular type adapted to knitting fingers on knitted gloves, although it may be used for knitting any type of tubular fabric.

In the manufacture of woolen gloves it is customary to knit the wrist and hand portions on the usual machines, striping in cotton when the hand portion is completed, and thereafter to pick up the stitches for each finger and to knit each finger out individually, closing the end to form the completed glove. In many cases this is done by hand or by complicated small machines which are inefficient in operation and which do not produce the proper type of work. Moreover, the process is slow and therefore costly.

An object of this invention is to provide a machine for the knitting of glove fingers and similar small tubular articles, which will be simple and foolproof in operation and which may be more rapidly operated.

A further object is the provision of a machine which may be so mounted that the stitches may be simply and quickly placed on the needles with a saving of time and effort on the part of the operator.

A still further object is to provide a machine of the character described which may be simply and readily adjusted for different types of yarns and operation.

In the accompanying drawings:

Fig. 1 is a plan view of a preferred embodiment of my invention;

Fig. 2 is a cross sectional view taken on the line 2—2 of Fig. 1;

Fig. 3 is a cross sectional plan view taken on the line 3—3 of Fig. 2;

Fig. 4 is a cross sectional view on the line 4—4 of Fig. 1.

My machine 10 is designed to be mounted on an arm 11 which may be bolted to a table or stand so that the bottom of the machine is clear and readily accessible. The machine consists of two main parts, a base plate 12, which is stationary, and a rotating plate 14. The base plate 12 serves not only as a base, but as a needle plate, and is provided with a series of grooves 15 extending radially from the inner periphery 16 to the outer periphery 17. Adjacent the inward terminus of the grooves are a series of posts 18 which serve as further guides. The number of grooves 15 depends on the type of work to be done and the number of needles to be carried, there being one groove for each needle.

The needles 20 are of the conventional type

having a shank 21, a hook 22, and a latch 23. Each needle is provided with a butt 24. The needles are seated in the grooves so that the butts 24 extend above the surface of the base plate 12. 5 The rotating plate 14 is circular, and its outer periphery 25 is grooved at 26 to constitute a pulley wheel adapted to be engaged by the belt 27. The plate 14 has a depending annular flange, the inner portion of which, 28, is adapted to engage the periphery 17 of the base plate 12.

The undersurface of the plate 14 is provided with a cam groove 30 extending from the point 31 radially to the point 32. The cam groove 30 engages the butts of the needles to position them 15 within the needle grooves 15. Between the points 31 and 32, in a counter-clockwise direction, are guide cams or plates 33, 34, 35 and 36, positioned by the screws 37. These plates are readily removable to change the course of the needles when necessary, and the plate 34 is positioned by the screw 40 mounted in the elongated slot 41 so that the cam plate 34 may be adjusted without removal from the plate 14.

Mounted on the plate 14, by means of the 25 screw 45, is the arm 46 having a depending member 47 to be positioned in the opening 48 to form a gate for the convenient removal and insertion of the needles. The plate 14 is positioned on the base plate 12 by means of the plates 49 held by 30 the screws 50. A series of these plates may be used, or a continuous ring may be used to prevent the accidental removal of the plate 14.

Mounted on the plate 14 is a combined thread feeder and latch opener 55 held in place by the 35 screws 56. This member consists of an arm extending over the opening within the plates and is provided with apertures 57 and 59 through which the yarn is fed. It is also provided with an arcuate hook member 58 which acts as a latch opener and which opens the latches on the 40 needles so that the new stitch can be picked up by the hooks.

The entire machine may be run with a small 45 motor or foot treadle and is operated by the belt 27. In operation, particularly in the knitting of glove fingers, the stitches of the blank are picked up on the needles 20, the yarn is then fed through the apertures 57 and 59, and the top rotating plate 14 rotated in a clockwise direction. The 50 butts 24 of the needles being engaged by the track 30, will be held in position until they engage the track 39, defined by the cam plates 33, 34, 35 and 36, where the knitting operation is controlled, the needles being extended by the track at 38 and then withdrawn by the track at 39, thereby cast-

ing off the old stitch. A shoulder 60 is provided on the cam plate 34 to prevent rotation of the plate in a counter-clockwise direction.

It will be appreciated that the needles operate in a horizontal plane and that, in picking up the stitches, the operator may freely hold the work under the machine without running into any obstructions. Since the needles are operated in a horizontal plane, the stitches may be easily and quickly picked up.

In order to facilitate the operation of the machine and to make more readily accessible the needles, the under portion of the plate 12 is cut away at 65 and 66, as is shown particularly in Fig. 2. This makes it much simpler for the operator to pick up stitches from the blank.

I claim:

1. A circular knitting machine comprising a stationary base plate, a plurality of needle grooves radially disposed in said base plate, needles having latches in said grooves with their butts extending above said grooves, a cam plate having a cam track engaging said needle butts mounted on said stationary plate, the periphery of said cam plate forming a pulley wheel, a belt in said pulley wheel, and a combined yarn feeder and latch opener mounted on said cam plate.

2. A circular knitting machine comprising a stationary base plate, means for mounting said base plate whereby the bottom thereof will be free from obstruction, a plurality of needle grooves radially disposed in said base plate, needles having latches and butts positioned for sliding movement in said grooves with their butts extending above said grooves, a cam plate having a cam track engaging said needle butts mounted for rotation on said stationary plate, the periphery of said cam plate forming a pulley wheel, and said cam track having adjustable cam plates to vary the degree of movement of said needles in said grooves.

3. A circular knitting machine comprising a stationary base plate, an opening in the center of said base plate, means for mounting said base plate whereby the bottom thereof and the opening therein will be free from obstruction, needle grooves radially disposed in said base plate, needles having latches and butts in said grooves with the operating end of said needles in said

opening, a cam plate mounted for rotation on said stationary base plate, the periphery of said cam plate forming a pulley wheel, an opening in the center of said cam plate above said needles, a combined yarn feeder and latch opener mounted on said base plate over said opening and over said needles.

4. A circular knitting machine comprising a stationary base plate, a plurality of needle grooves radially disposed in said base plate, needles having latches in said grooves with their butts extending above said base plate, a cam plate having a cam track engaging said needle butts mounted for rotation on said stationary plate, an opening in said cam plate for said needles, a combined yarn feeder and latch opener mounted on said cam plate over said needles, an opening in said cam plate extending from said cam track to the inner periphery of said cam plate whereby said needles may be removed without removing the cam plate, and a gate for said opening.

5. A circular knitting machine comprising a stationary base plate having a central opening therein, the under portion of said base plate adjacent said opening being cut away, means for mounting said base plate whereby the under portion thereof will be unobstructed, radially disposed needle grooves in said base plate, needles having latches disposed in said grooves with their butts extending above said base plate, a radial cam plate carrying a cam track mounted for rotation on said base plate, the outer periphery of said cam plate forming a pulley wheel, a belt engaging said pulley wheel, and a combined yarn feeder and latch opener mounted on said cam plate for rotation therewith.

6. A circular knitting machine comprising a circular base plate, a plurality of needle grooves radially disposed in said base plate, needles in said grooves with their butts extending above said grooves, a cam plate having a cam track engaging said needle butts mounted on said stationary plate, the periphery of said cam plate forming a pulley wheel, a belt on said pulley wheel, and means for feeding yarn to said needles mounted on said cam plate.

WILLIAM J. KUEHNEL.
